UNITED STATES PATENT OFFICE.

MARSHALL J. HATCHER, OF MACON, GEORGIA.

CAR-AXLE.

SPECIFICATION forming part of Letters Patent No. 366,953, dated July 19, 1887.

Application filed May 2, 1887. Serial No. 236,832. (No model.)

To all whom it may concern:

Be it known that I, MARSHALL J. HATCHER, a citizen of the United States, and a resident of Macon, county of Bibb, State of Georgia, 5 have invented new and useful Improvements in Axles for Cars, &c., of which the following is a full and exact description, reference being had to the accompanying drawings, making part of this specification.

10 My invention consists in the combination, with a tubular axle, of reversible boxes adapted to fit in the ends thereof, and reversible spindles for operating in said boxes, and for receiving the traction-wheels of car or 15 wagons and other vehicles.

My improvements will be readily understood by referring to the accompanying drawings, whereon Figure 1 represents the opposite ends of an axle provided with the improvements, one end being shown in section. Fig. 2 is a perspective view of one of the reversible boxes. Fig. 3 is a similar view of a journal-box with the central groove omitted. Fig. 4 is a like view of one of the reversible 25 spindles with end collars or heads separated therefrom, and Fig. 5 is a perspective view of an axle having a square end and a detached reversible box adapted to fit therein.

The letter A designates the tubular axle; B, 30 a reversible journal-box adapted to fit within one end of said axle.

C C are set-screws for holding the boxes in fixed positions within the axle ends, or for preventing any end-play of said boxes.

35 D are the reversible spindles, and E the collars, which are loosely or rigidly fitted on the spindles midway between the ends thereof. The ends of the spindles are drilled and tapped, or provided with screw-threads, to receive 40 the screw-threaded portions of the end collars or heads, F.

The journal-boxes are bored out to the diameter of the wheel-hubs, and both boxes and hubs are made of equal lengths, in order to receive either end of the reversible spindles D.

A slight channel, h, is formed around the center of each journal-box to receive the ends of the set-screws C C', whereby any end-movement of the box is effectually prevented, even

when the said boxes are permitted to run 50 loosely within the axle.

Another advantage in forming a channel around the box is that in event of any injury being done to the surface of the box by the action of the set-screws pressing against same, 55 the injured parts will not come in contact with the tube and thus jam the box within same, as would be the case were there no channel made around the box, as stated.

Instead of the axle being cylindrical in form, 60 as shown in Fig. 1, it may be made with one or more flat sides, or with its body round and ends square, as shown in Fig. 5, in which event the outer diameter of the journal-boxes should be made of similar form to the ends of the 65 axle.

In the application of my invention the end collars or heads are first removed from the spindles, which, if not already provided with central collars, next have said collars slipped 70 thereon. One end of the spindle is then inserted in one of the journal-boxes, wherein it is held by the outer collar, which is next screwed on or into the end of the spindle for said purpose. The box, with its spindle, is 75 then inserted within one end of the axle and the set-screws applied in the side perforations thereof until the points of the said screws enter the channel around the journal-box and come in contact or in close proximity with the 80 bottom of said channel. The wheels are then applied to the outer ends of the spindles and the remaining end collars or heads applied to hold same thereon.

Having described my invention, what I claim 85 as new, and desire to secure by Letters Patent, is—

1. The combination of a tubular axle provided with set-screws, as described, with reversible journal-boxes adapted to fit within 90 the ends of said axle and form bearings for the inner ends of the wheel-spindles, substantially as and for the purpose set forth.

2. In combination with a tubular axle, the reversible journal-boxes adapted to fit in the 95 ends thereof, the reversible boxes each provided with a central groove around its outer diameter, and the outer portions of the axle

provided with set-screws for engaging the said groove, substantially as and for the purpose specified.

3. In combination with a tubular axle and the journal-boxes fitted in the ends thereof, the reversible spindles having central collars, substantially as and for the purpose set forth.

4. A reversible spindle having a central collar, either fixed or loose, as described, and

the detached end collars or heads, with a tubular axle provided with end journal-boxes, substantially as and for the purpose specified.

In testimony whereof I affix my signature in presence of two witnesses.

M. J. HATCHER.
